(57) **CLAIM**

We claim the ornamental design for a candle, as shown and described.

DESCRIPTION

FIG. 1 is a top perspective view of a candle showing our new candle;

FIG. 2 is a front view of the candle design of FIG. 1;

FIG. 3 is a rear view of the candle design of FIG. 1;

FIG. 4 is a right side view of the candle design of FIG. 1;

FIG. 5 is a left side view of the candle design of FIG. 1; and,

FIG. 6 is a top view of the candle design of FIG. 1. The broken lines in the drawings depict portions of the candle that form no part of the claimed design.
